(57) **CLAIM**

The ornamental design for a breast milk storage container, as shown and described.

DESCRIPTION

FIG. 1 is an exploded isometric view of a breast milk storage container showing my new design, with unclaimed cap and nipple not attached;

FIG. 2 is an isometric view thereof, with unclaimed cap and nipple attached;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines illustrate environmental components of the breast milk storage container which form no part of the claimed design.
